CLOCK FACE

Marion K. Summers, W. Commerce St.,
Brownstown, Ind. 47220

Filed Apr. 8, 1966, Ser. No. 1,816

Term of patent 14 years

Int. Cl. D10—06

U.S. Cl. D42—7

FIG. 1.

FIG. 2.

FIG. 1 is a front elevational view of a clock face showing my new design; and

FIG. 2 is a bottom view thereof.

The dominant features of my design reside in those portions shown in full line. Stylized coin representations of a dollar coinage system are shown in broken lines.

I claim:

The ornamental design for a clock face, substantially as shown and described.
